(57) **CLAIM**

I claim the ornamental design for a soil sampling device, substantially as shown and described.

DESCRIPTION

FIG. 1 is a perspective view of a soil sampling device showing the new design for a soil sampling device; FIG. 2 is a right side view of the soil sampling device, showing the main part of the soil sampling device on which user interaction will occur;

FIG. 3 is a rear view of the soil sampling device;

FIG. 4 is a left side view of the soil sampling device;

FIG. 5 is a front view of the soil sampling device;

FIG. 6 is a top view of the soil sampling device; and,

FIG. 7 is a bottom view.
